UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

Application filed January 28, 1921. Serial No. 440,645.

This invention comprehends improvements of general utility in the coking retort oven art, and also comprehends certain improvements especially applicable to coking retort ovens of the well-known cross-regenerative type exemplified in the patent to H. Koppers No. 818,033 dated April 17, 1906.

The invention has for objects the provision of a coking retort oven having, as an important characteristic, a novel construction of the heating walls and system of control of the flow through the flame flues of said walls and their communicably connected regenerators, which eliminates the employment of horizontal or bus flues in the oven construction. The improvements made by the invention have the important advantage that they enable a considerable thickening and strengthening of the upper region of the walls of the oven structure.

In addition to the objects recited above, the invention contemplates a novel regenerative construction and system of flow therethrough and through the flues, promoting uniformity of distribution, and has for other objects such other improvements and advantages in construction and operation as are found to obtain in the structures and devices hereinafter described or claimed.

In the accompanying drawings, forming a part of this specification and showing, for purposes of exemplification, a preferred form and manner in which the invention may be embodied and practiced, but without limiting the claimed invention to such illustrative instance or instances:

Figure 1 is a crosswise vertical section through a coke oven battery embodying features above specified and equipped with the improvements of the present invention, the view being taken longitudinally through a coking chamber and a pair of regenerators, in planes indicated by the line A, A of Fig. 2;

Fig. 2 is a composite vertical sectional elevation taken longitudinally of a coke oven battery, in planes indicated by the lines D, D, E, E and G, G of Fig. 3; and

Fig. 3 is a composite vertical sectional elevation taken transversely of a coke oven battery, in planes indicated by the lines B, B and C, C of Fig. 2.

The same characters of reference designate the same parts throughout the several views of the drawings.

In the embodiment illustrated in the drawings, the invention is incorporated in a combination coke oven battery, i. e., a battery having provision for being operated either with producer gas for fuel or with coke oven gas burned in an atmosphere of ordinary preheated air such as is utilized in ordinary coke ovens or with coke oven gas burned in an atmosphere containing both air and a neutral gaseous diluent which is introduced into the flame flues separately from the air. A combination coke oven battery having these features is described and claimed in my Patent No. 1,416,322, for coking retort oven, dated May 16, 1922. For convenience, the present description will be confined to the present illustrated embodiment of the invention in such a coke oven battery; the novel features and improvements made by the invention are susceptible of other applications, such, for example, as ordinary so-called "coke ovens" employing coke oven gas for fuel, or ordinary so-called "gas ovens" employing producer gas for fuel; hence, the scope of the invention is not confined to the specific use and specific embodiment herein described as an illustrative example.

Referring to the drawings: there are illustrated views of a coke oven battery or plant of the by-product type, having features above specified; said oven battery embodies in its construction a plurality of crosswise elongated heating walls 11, 11 and a plurality of intermediate crosswise elongated vertical coking chambers 12, 12. The heating walls 11 form the side walls of the respective coking chambers 12, as shown more particularly in Fig. 2, and, in the present instance, are supported by the heavy supporting or pillar walls 13, 13 which extend crosswise of the battery and are located, as shown in Fig. 2, in pairs beneath the respective heating walls 11, 11. These pillar walls, together with other walls, hereinafter described, collectively form the main support for the entire superstructure of the oven battery, and are themselves supported upon a flat mat or platform which constitutes the sub-foundation on which the entire battery rests.

The coal to be coked is charged into the several coking chambers or ovens through charging holes 14 located in the top 15 of the oven battery and positioned directly

above the ovens or chambers 12, as shown in Figs. 1 and 2. These charging holes 14 are equipped with the usual removable covers, which are removed during charging of the individual ovens or coking chambers and are placed in position to close the tops of such coking chambers during the entire coking or distilling operation. The gases of distillation pass from the tops of the several coking chambers 12 through gas outlets 16 and thence through ascension pipes (not shown) into the usual gas collecting main which carries the distillation products to the by-product recovery apparatus.

Heat for coking the charges of coal in the several ovens or chambers 12 is derived from the heating walls 11, which as before mentioned, extend crosswise of the battery at the sides of the coking chambers. Referring now more particularly to Figs. 2 and 3, each heating wall 11 is constituted of two parallel series G and H of flame or combustion flues 17. Each series of such flame flues extends from end to end of the heating wall and, in accordance with the invention all of the flues of one series of a heating wall operate concurrently for flow in the same direction while, at the same time, all of the flues of the other series of the same heating wall are operating concurrently for flow in the opposite direction. When the series of flues on one side of a coking chamber are burning, that is to say, operating for upflow the flame flues on the opposite side of the same coking chamber are operating for downflow to permit exhaust of the waste gases. Consequently heating is maintained continuously from end to end on one side of a charge of coking coal in each coking chamber, the heat being applied to the full length of one side of such charge during an entire period and, then, after reversal, being applied to the full length of the opposite side of the charge, until a subsequent reversal is effected. The wall section 17' separating the respective series of flues 17 in each wall are preferably made of substantial thickness as clearly shown in Figure 2 to prevent the escape of the burning gases therethrough from the combustion flues into the waste gas flues as tends to occur due to the pressure differential at the bottoms of the respective flue series. This construction also results in greatly strengthening the walls and permits the building of higher walls and flues, which is a very desirable feature, as well as facilitating the introduction of the requisite number of regenerators.

The crosswise regenerators 18 of the regenerator oven or battery are located at a lower level than the aforesaid heating walls 11 and coking chambers 12 and, in the present instance, extend in parallelism between the pillar walls 13 and the other heavy supporting walls hereinafter described. Lo-

cated in the middle lengthwise vertical plane of the coke oven battery, is a vertical partition 19, as shown in Fig. 1, which partition extends all the way up from the mat of the battery to the bottom of the overlying coking chamber and from one to the other of the pillar walls 13, and the other walls which are between the pillar walls. The regenerators, which are respectively located on opposite sides of the battery extend inwardly 70 to said partition 19 and are separated thereby as clearly shown in Fig. 1. This arrangement permits control from opposite sides of the battery of the flow through the regenerators, thereby assisting the novel flue 75 arrangement in promoting uniformity of distribution. Each regenerator 18 is a chamber containing open brickwork commonly called checkerwork, and indicated at 20, with a distributing sole channel 21 underneath such checkerwork, the channels forming the soles of such chambers and opening up into the checkerwork.

In accordance with the present embodiment of the invention, a heavy vertical gas-tight supporting wall 22 extends in parallelism between each two adjacent pillar walls 13 and such supporting walls 22 provide two regenerators located respectively on the opposite sides of such walls 22 and between adjacent pillar walls 13. The several walls 22 also have the function with the pillar walls 13 of supporting the weight of the battery superstructure. As shown in Fig. 2, the adjacent regenerators which are communicably connected with the series G of flame flues are respectively designated by the reference characters G' and the adjacent regenerators which are communicably connected with the series H of flame flues are respectively designated by the reference character H'.

The regenerators G' and H' are heated, in alternation, by the hot combustion products that are exhausted from the flame or combustion flues hereinbefore mentioned and then impart such heat to the medium that they feed into these flame flues; in the present instance, the flow through the pair of adjacent regenerators G' on each side of the battery is maintained concurrently in the same direction while the flow in the pairs of adjacent regenerators H' on each side of the battery is also maintained concurrently in the same direction but in the opposite direction respectively to the flow 115 through the pairs of regenerators G'. Each regenerator is provided with a series of ducts 23 all of which lead respectively to individual flame flues 17 of the same heating wall. According to the invention the pairs 120 of regenerators of the groups H' are communicably connected by such ducts 23 with the flues of the series H of the heating walls, and the pairs of regenerators of the group G are communicably connected by similar ducts 125 130

23 with the flame flues of the series G of the heating walls. With this construction, each flame flue 17 of both series of each heating wall communicates by a pair of ducts 23 5 with adjacent separate regenerators through which flow is maintained concurrently in the same direction, that is to say both of the regenerators which are connected with the same series of flame flues are either operating for inflow or for outflow. As shown in Fig. 2, the pairs of regenerators of the groups G' alternate with the pairs of regenerators of the groups H'. In the present embodiment of the invention, an entire series of flame flues G or H of each heating wall is either burning or operating for downflow to convey waste products to the regenerators beneath, while the other series of the same heating wall is 10 operating for flow in a direction opposite to that in the series of flues just mentioned, and consequently the regenerators aligned on opposite sides of the central longitudinal partition 19 operate concurrently for flow 15 in the same direction and in the same manner. The reversal in flow through the flame flues on opposite sides of a coking chamber, and their communicably connected regenerators may thus be said to take place longitudinally of the oven battery, instead of transversely thereof, as has heretofore been a common practice in this art. The reversal of the oven is effected at the end of an operating period determined by practice, and by 20 means of any preferred type of reversing mechanism. The function of such reversal is as follows: The regenerators and flues that prior to the reversal operated as inflow 25 regenerators and flues become outflow regenerators and flues, and the outflow operating regenerators and flues become inflow operating regenerators and flues; the supply of gas is turned off from the previously upburning flues and turned into the mains of 30 the previously downburning flues. Each flame flue 17 of both series of each heating wall has at its top a port or opening 24 for draft and the passage of combustion products or waste gas from the flame within the 35 flue. In accordance with the invention, these ports 24 open up into passageways 25, there being a passageway 25 connecting each flue of a series G individually with the contiguous flue of the series H of the same heating wall. Thus all of the flues of a series G of a heating wall are individually connected by longitudinally extending passage ways 25 with the contiguous flues of the other group of the other series H of the 40 same heating wall. By reason of the fact that the several passageways 25 of each heating wall are only required to have sufficient capacity for taking care of the flow from an individual flue and directing it into 45 another individual flue, the thickness and strength of the heating walls are substantially increased in the region where one series of flame flues is connected with another. Moreover, because of the fact that, in the present instance, the upburning flues 70 are individually connected with the downburning flues, uniformity in distribution of the flow through the flues and the communicating regenerators is greatly promoted. The draft through the ports 24 may be 75 regulated by means of the usual movable dampers or sliding bricks 27, positioned in the ordinary way in the bottoms of the connecting passageways 25 and adapted to be reached by access flues 28 which extend from 80 the top of the passageways 25 in each heating wall to the top 15 of the battery, there being an access flue positioned over each flame or combustion flue of each heating wall. 85 Extending crosswise of the battery in each pillar wall 13 and located beneath the heating wall 11 thereabove, is a pair of gas-supply channels 29 and 30. These channels 29 and 30 are for the purpose of supplying 90 coke oven gas to the several flame flues on each side of the central line L, and to accomplish this end, the channel 29 communicates with the individual flues 17 on one side of said line L by means of ducts 31 that lead 95 from such channel 29 individually into the bottoms of individual flues; and the channel 30 which supplies the several flues that are located on the other side of the above mentioned dividing line L communicates therewith by means of similarly connecting ducts. 100 Within the several ducts are disposed the usual nozzles 32. The supply of coke oven gas to the respective channels 29 and 30 is derived from coke 105 oven gas means of the usual type and respectively located on the opposite sides of the battery and extending longitudinally therewith. Suitable means is provided for admitting or cutting off the supply of gas with respect to each pair of channels 29 and 30, it being understood that the gas supply is either concurrently maintained or concurrently shut off from both channels of a pair. 110 For operating the battery alternately with the use of a special generator gas, such as producer gas for fuel, one regenerator of each pair H' or G', this depending on which group is operating for inflow, may be optionally connected with a producer gas main, 115 by mechanism such as is disclosed in my before mentioned Patent No. 1,416,342, so that producer gas may be directed into one regenerator of each inflow operating pair and air into the other regenerator of each such pair, the air and producer gas being 120 conveyed through these regenerators into burning flame flues. 125 The operation of the battery, when using a special generator gas, such as ordinary 130

producer gas for fuel, is as follows: The supply of coke oven gas to the coke oven gas main and to all of the coke oven gas channels 29 and 30 is cut off. Assuming that the flue series H and their connected pairs of regenerators of the group H' are operating for inflow, a supply of producer gas is permitted to flow into one regenerator of each pair H' and air into the other regenerator of each such pair. During the inflow of producer gas and air through the regenerators H' waste gas from the downburning flues of the series G is flowing out through the communicably connected regenerators of the groups G'. On reversal of the battery the inflow operating regenerators H' and flues H become outflow regenerators and flues and concurrently the outflow operating regenerators G' and flues G become inflow regenerators and flues.

In operating the battery with coke oven gas in the ordinary manner, the supply of producer gas to one member of each inflow operating pair of regenerators is shut off and air is permitted to flow into such regenerators in place of the producer gas. During coke oven gas operation, a supply of coke oven gas is maintained in such of the channels 29 and 30 as feed the upburning flues. The reversing mechanism is operated at each reversal to place all of the inflow operating regenerators in communication with the outer air and concurrently all of the outflow operating regenerators in communication with the exhaust. A further mode of operation is with coke oven gas as a fuel; combined with a supply of neutral gaseous diluent to the upburning flues. In so operating the battery, the supply of producer gas is turned off and the supply of coke oven gas is turned on. Instead however of permitting air to flow into such regenerators of the inflow operating groups that serve for producer gas, during the latter operation, waste gas is permitted to flow into such regenerators and be delivered thereby to the upburning flame flues. The admission into each of the upburning flues of a supply of neutral gaseous diluent, such as waste gas, is effective to lengthen greatly the flames within such flues and to prevent the localization of the hottest flame temperature in the extreme lower portions of the flues.

The invention as hereinabove set forth is embodied in a particular form of construction but may be variously embodied within the scope of the claims hereinafter made.

I claim:

1. In a coking retort oven, in combination: a plurality of parallel coking chambers; heating walls between and contiguous to such coking chambers and respectively constituted of two parallel series of vertical combustion flues, the individual combustion

flues of one series being individually connected with the individual combustion flues of the other series of the same heating wall; individually regulable and reversible regenerators parallel with the coking chambers and the heating walls, such regenerators being communicably connected in pairs with each series of such combustion flues, the pairs of such regenerators being individual to the series of combustion flues with which they are connected; and means for separately controlling the individual flow through individual regenerators and their connected series of combustion flues; substantially as specified. 80

2. In a coke oven battery, in combination: a plurality of parallel coking chambers; heating walls between and contiguous to such coking chambers and respectively constituted of two parallel series of vertical combustion flues, the individual flues of one series being communicably connected transversely of the heating walls with the individual flues of another series of the same heating wall; and individually regulable and reversible regenerators parallel with the coking chambers and the heating walls, such regenerators being grouped side-by-side into pairs and each pair of the regenerators being communicably connected with a single series of such combustion flues, the pairs of such regenerators being individual to the series of combustion flues with which they are connected; substantially as specified. 95

3. In a coke oven battery, in combination: a plurality of parallel coking chambers; heating walls between and contiguous to such coking chambers and respectively constituted of two parallel series of vertical combustion flues, the individual flues of one series being communicably connected transversely of the heating walls with the individual flues of another series of the same heating walls; and individually regulable and reversible regenerators parallel with the coking chambers and the heating walls, such regenerators being grouped side-by-side into pairs and alternate pairs of the regenerators being respectively connected with one series of combustion flues of the heating walls and the pairs of regenerators which are intermediate such alternate pairs being communicably connected with the other series of combustion flues of the heating walls, the pairs of such regenerators being individual to the series of combustion flues with which they are connected; substantially as specified. 115

4. In a coking retort oven, in combination: a plurality of coking chambers; heating walls contiguous to such coking chambers and respectively constituted of more than one similar series of vertical combustion flues of which each single flue of one series is connected with a corresponding single flue of another; and regenerators grouped into 125 130

5 pairs, each pair of such regenerators being communicably connected with one series of such combustion flues, the pairs of such regenerators being individual to the series of combustion flues with which they are connected; substantially as specified.

10 5. In a coking retort oven, in combination: a plurality of coking chambers; heating walls contiguous to such coking chambers and respectively constituted of two similar series of vertical combustion flues of which each single flue of one series is connected with a corresponding single flue of the other; and regenerators grouped into pairs, 15 each pair of such regenerators being communicably connected with a single series of such combustion flues, the pairs of such regenerators being individual to the series of combustion flues with which they are connected; substantially as specified.

20 6. In a coking retort oven, in combination: a plurality of coking chambers; heating walls contiguous to such coking chambers and respectively constituted of more than one parallel series of vertical combustion flues, one series of such flues being communicably connected with another series of such flues; and regenerators grouped into pairs, each pair of such regenerators being 25 communicably connected with a single series of such combustion flues, the pairs of such regenerators being individual to the series of combustion flues with which they are connected; substantially as specified.

30 7. In a coking retort oven, in combination: a plurality of coking chambers; heating walls contiguous to such coking chambers and respectively constituted of two similar series of combustion flues of which each single flue of one series is connected with the corresponding single flue of the other; and regenerators grouped into pairs, each pair of such regenerators being communicably connected with a single series of such combustion flues, the pairs of such regenerators being individual to the series of combustion flues with which they are connected; substantially as specified.

35 8. In a coking retort oven, in combination: a plurality of coking chambers; heating walls contiguous to such coking chambers and respectively constituted of more than one parallel series of combustion flues, one series of such flues being communicably connected with another series of such flues; and regenerators grouped into pairs, one pair of such regenerators being communicably connected with one series of such combustion flues, and another pair of such regenerators being communicably connected with the other series of such flues, the pairs of such regenerators being individual to the series of combustion flues with which they are connected; substantially as specified.

40 9. In a coking retort oven, in combina-

tion: a plurality of coking chambers; heating walls contiguous to such coking chambers and respectively constituted of a plurality of similar series of combustion flues of which each single flue of one series is connected with the corresponding single flue of another series; and regenerators grouped into pairs, a pair of such regenerators being communicably connected with one series of such combustion flues, and another pair of such regenerators being communicably connected with the other series of such flues, the respective pairs of such regenerators being individual to the series of combustion flues with which they are connected; substantially as specified.

45 10. In a coking retort oven, in combination: a plurality of parallel coking chambers; heating walls between and contiguous to such coking chambers and respectively constituted of two series of vertical combustion flues of which each single flue of one series is communicably connected with a corresponding single flue of the other series, so as to allow flow in one series simultaneously counter to that in the other, said series lying respectively on the opposite sides of their respective heating walls and being separated from each other by partition walls that, to prevent leakage of gas from one to the other, are substantially thicker than the flue-walls facing the coking-chambers, the said thick partition being proportioned as a massive division wall and adapted to be gas-tight against extremes of pressure-differential between the mutually opposite counter-current branches of the long flow-path through the combustion-flues that parallel each other on opposite sides of said wall and are interconnected through its top; and regenerators parallel to the heating walls and communicably connected to said flues; substantially as specified.

50 11. In a coking retort oven, in combination: a plurality of parallel coking chambers; heating walls between and contiguous to such coking chambers and respectively constituted of two series of combustion flues, communicably connected so as to allow flow in one series simultaneously counter to that in the other, said series lying respectively on the opposite sides of their respective heating walls and being separated from each other by partition walls that, to prevent leakage of gas from one to the other, are substantially thicker than the flue-walls facing the coking-chambers, the said thick partition being proportioned as a massive division wall and adapted to be gas-tight against extremes of pressure-differential between the mutually opposite counter-current branches of the long flow-path through the combustion-flues that parallel each other on opposite sides of said wall and are interconnected through its top; and re-

generators parallel to the heating walls and communicably connected to said flues; substantially as specified.

12. In a coking retort oven, in combination: a plurality of parallel coking chambers; heating walls between and contiguous to such coking chambers, one of said heating walls comprising combustion flues lying respectively on the opposite sides thereof and separated from each other by a partition wall substantially thicker than the flue-walls facing the coking-chambers, said flues on said opposite sides being parallel to each other and communicably connected together, so that a gas flow in said flues may be simultaneously counter-current on the opposite sides of said partition wall; and regenerators parallel to the heating walls and communicably connected to said flues, said regenerators being all located laterally of each other and arranged in groups respectively adapted to convey to said flues air or air and a preheated combustible gas and to remove the waste gases therefrom in alternation, and means for supplying at will to said flues an unpreheated combustible gas.

13. In a coking retort oven, in combination: a plurality of parallel coking chambers; heating walls between and contiguous to such coking chambers, one of said heating walls comprising combustion flues lying respectively on the opposite sides thereof and separated from each other by partition wall substantially thicker than the flue-walls facing the coking-chambers, said flues on said opposite sides being parallel to each other and communicably connected together, so that a gas flow in said flues may be simultaneously counter-current on the opposite sides of said partition wall and regenerators parallel to the heating-walls and communicably connected to said flues and arranged in groups respectively adapted to convey to said flues air or air and a preheated combustible gas and to remove the waste gases therefrom in alternation, and means for supplying at will to said flues an unpreheated combustible gas.

14. In a coking retort oven, in combination: a plurality of parallel coking chambers; heating walls between and contiguous to such coking chambers, one of said heating walls comprising combustion flues lying respectively on the opposite sides thereof and separated from each other by a partition wall substantially thicker than the flue-walls facing the coking-chambers, said flues on said opposite sides being parallel to each other and communicably connected together, so that a gas flow in said flues may be simultaneously counter-current on the opposite sides of said partition wall and regenerators parallel to the heating-walls and communicably connected to said flues, said regenerators being all located laterally of each other

and arranged in groups respectively adapted to convey to said flues air and a preheated combustible gas and to remove the waste gases therefrom in alternation.

15. In a coking retort oven, in combination: a plurality of parallel coking chambers; heating walls between and contiguous to such coking chambers, each of said walls being constituted of two parallel sets of combustion flues; means communicably interconnecting said sets transversely of said walls; said connected combustion flues being separated from each other by partition walls that are substantially thicker than the flue-walls facing the coking-chambers; and regenerators parallel to the heating-walls and communicably connected to said flues and arranged in groups respectively adapted in alternation to convey to said flues air or air and a preheated combustible gas and to remove the waste gases therefrom, and means for supplying at will to said flues an unpreheated combustible gas.

16. In a coking retort oven, in combination: a plurality of parallel coking chambers; heating walls between and contiguous to such coking chambers, each of said walls being constituted of two parallel sets of combustion flues; means communicably interconnecting said sets transversely of said walls; said connected combustion flues being separated from each other by partition walls that are substantially thicker than the flue-walls facing the coking-chambers; and regenerators parallel to the heating-walls and communicably connected to said flues and arranged in groups respectively adapted in alternation to convey to said flues air and a preheated combustible gas and to remove the waste gases therefrom.

17. In a coking retort oven, in combination: a plurality of parallel coking chambers; heating walls between and contiguous to such coking chambers and respectively constituted of two series of vertical combustion flues, communicably connected with each other so as to allow flow in one series simultaneously counter to that in the other, said series lying respectively on the opposite sides of their respective heating walls and being separated from each other by partition walls that are substantially thicker than the flue-walls facing the coking-chambers; and two series of inspection holes, for said flues, through the oven top, above and registering with the two series of combustion flues that lie on opposite side of the thick partition wall.

18. In a coking retort oven, the combination claimed in claim 11 and in which the tops of said two series, together with the communication between them, are isolated from the top portions of the coking-chambers respectively adjacent said series by walls substantially thicker than the flue-walls facing

the coking-chambers at levels lower than said top portions thereof.

19. In a coking retort oven, in combination: a plurality of parallel coking chambers; heating walls between and contiguous to such coking chambers and respectively constituted of vertical combustion flues communicably connected in pairs, each pair comprising two combustion-flues adapted for reversal of flow from one to the other and for simultaneous flow in counter-current with each other; said connected combustion flues being separated from each other by partition walls that are substantially thicker than the flue-walls facing the coking-chambers; and a crosswise regenerative system arranged be-

low and communicating with the flues of said heating walls by upwardly directed ducts substantially individual to the flues, some of the regenerators, during the inflow period, operating to convey to said flues an extraneously derived gas, such as producer gas, and some to convey air, the said air-regenerator ducts and the said air-regenerator ducts for each heating-wall being of substantially the same proportions and locations relative to those for the several other heating-walls to promote substantial equality between the heating-walls as to flow between them and the regenerators respectively serving them. 25 30

JOSEPH BECKER.
